COMBINED CONTAINER OPENER AND CORKSCREW

Fred S. Steiner, Woodmere, N.Y., assignor to Bonny
Products, Inc., Lynbrook, N.Y., a corporation of
New York

Filed Apr. 17, 1968, Ser. No. 11,484

Term of patent 14 years

Int. Cl. D8—02

U.S. Cl. D44—29

FIG. 2

FIG. 3

FIG. 1 is a perspective view of a combined container opener, and corkscrew, showing my new design;
 FIG. 2 is an enlarged scale top plan view;
 FIG. 3 is an enlarged scale bottom plan view;
 FIG. 4 is a front elevational view;
 FIG. 5 is a right side elevational view;
 FIG. 6 is a rear elevational view; and
 FIG. 7 is a left side elevational view.

I claim:
 The ornamental design for a combined container opener and corkscrew, as shown.
